UNITED STATES PATENT OFFICE.

HENRY LEIMAN, OF NEW YORK, N. Y.

CIGAR-BOX-TRIMMING MACHINE.

SPECIFICATION forming part of Letters Patent No. 460,877, dated October 6, 1891.

Application filed September 19, 1890. Serial No. 365,478. (No model.)

To all whom it may concern:

Be it known that I, HENRY LEIMAN, of New York city, in the county and State of New York, have invented a new and Improved 5 Cigar-Box-Trimming Machine, of which the following is a full, clear, and exact description.

My invention relates to an improvement in cigar-box-trimming machines, and has for its 10 object to economize in the construction of such machines and to so simplify the mechanism and render it automatic to such an extent that the services of two unskilled laborers only will be required in the operation of 15 trimming to feed the boxes to the machine.

The invention consists in the novel construction and combination of the several parts, as will be hereinafter fully set forth, and pointed out in the claims.

Reference is to be had to the accompanying drawings, forming a part of this specification, in which similar figures of reference indicate corresponding parts in all the views.

Figure 1 is a front elevation of the machine 25 partially in section, the section being taken through and beneath the table, as indicated by the line 11 in Fig. 3. Fig. 2 is a plan view of the machine. Fig. 3 is an end elevation. Fig. 4 is a longitudinal section through a portion of 30 one of the saw-shafts and the pulley by means of which the shaft is rotated. Fig. 5 is a front elevation of a set of saw-shafts, illustrating the position occupied by the saws carried thereby with relation to the box to be trimmed; 35 and Fig. 6 is a plan view of one of the lower saw-shafts and its connected adjusting-bars.

The frame of the machine consists of two end pieces 10, properly braced and having a vertical extension 11 at one side, upon which 40 the bed 12 of the machine is laid and secured, the table 13 being also supported by the end pieces through the medium of suitable brackets, as shown in Fig. 3, the inner side of which table is spaced some distance from the bed. 45 Upon the bed 12 three upright carrier-blocks are supported, comprising an intermediate carrier 14 and two end carriers 15 and 16. The carrier-blocks are capable of sliding laterally upon the bed, being provided with dovetailed slots in their bases, receiving a similar 50 rib integral with the bed, as is best shown in Fig. 3. The center carrier is normally held

in one position by a set-screw or its equivalent; but the side carriers are laterally adjustable through the medium of horizontal screws 17, connected therewith and held to turn in suitable bearings 17^a, projected upward from the bed, being preferably manipulated through the medium of crank-arms applied to their outer ends. Upon the front upright 60 face of each carrier-block a bracket is held to slide vertically, which brackets are designated, respectively, as 18, 19, and 20, and said brackets are raised or lowered by screw-shafts 21, one of which shafts is journaled in each 65 carrier-block, the lower ends of the shafts being passed through lugs secured to the rear of the brackets, having threaded apertures therein, and the upper ends of the shaft are provided with bevel-gears 22, meshing with 70 similar gears 23, fast upon a line-shaft 24, journaled upon the upper ends of the carrier-blocks. The shaft 24 is preferably revolved through the medium of a crank-arm 25, as shown in Figs. 1 and 2. Beneath the 75 sliding brackets 18 and 20 of one end similar brackets 26 and 27 are rigidly secured to the blocks 14 and 16, the lower bracket being omitted from the other end carrier-block. All of the brackets are provided with 80 essentially triangular arms 27^a, projecting in the direction of the table, and in suitable bearings 28 at or near the apex of each bracket-arm a horizontal saw-shaft 29 is journaled, the ends whereof extend beyond the arms, 85 and in the base of the arm of each bracket two parallel adjusting-bars 30 and 31 are held to slide. When two brackets are attached to a carrier-block, the base of the upper bracket-arms faces the base of the lower bracket-arms, as is best shown in Fig. 5, and when one bracket only is employed the base of the 90 arms thereof faces downward.

The saw-shaft and adjusting-rods of the brackets attached to the outer carrier-block 95 16 are connected at their outer ends by a yoke 32, preferably of triangular form, and the inner ends of each set of adjusting-rods are united by a horizontal guide-bar 33, essentially L-shaped in cross-section, the saws 100 being mounted upon the inner ends of the shafts 29.

The attachments to the inner ends of the adjusting-rods and saw-shafts of the carrier-

block 16 are duplicated upon the contiguous ends of the adjusting-rods and saw-shafts of the brackets located upon the intermediate carrier-block 14, the other ends of the said parts being united by a yoke in like manner with the outer ends of the corresponding parts upon the end carrier-block 16, as is best shown in Figs. 1 and 2.

The yoke 32 of each bracket is connected with the opposed bracket-arm by a spring 34, the tendency of the said spring being to draw the yoke in the direction of the bracket-arm, as is best shown in Fig. 6.

The saw-shaft connected with the end carrier-block 15 has a saw attached at or near its inner extremity, the yoke connection with the adjusting-rods being at the opposite extremity.

When two saw-shafts are connected with a carrier-block they are not parallel with each other—as, for instance, the inner end of the upper shaft 29 of the end carrier 16, to which the saw is attached, is given a downward inclination and the corresponding end of the lower shaft is given an upward inclination. The corresponding ends of the shafts connected with the intermediate carrier are treated in like manner, the saw-carrying extremity of the shaft located upon the end carrier 15 being inclined downward. All of the saw-shafts are also out of parallelism with the front face of the carriers, the extremities to which the saws are attached all having a forward lateral inclination, except the shaft connected with the carrier 15, which is given a rearward inclination. The lateral inclination of the shafts is usually effected by transversely beveling the backs of the brackets in which the shafts are journaled, whereby one side edge 40 is thicker than the other. The saws, which are designated as 35 in the drawings, are therefore inclined slightly both laterally and vertically, as is best shown in Figs. 5 and 6. The vertical inclination of the saw-shafts is usually accomplished by placing the brackets diagonally upon the carriers. The object of inclining the saws is to cause them to engage with the edges of the box to be cut when the edges are immediately over or under the saws and to prevent the saws from engaging with the trimmed sides or ends of the box and lacerating the latter as the box is carried forward.

A hanger 37 is attached to the end carrier 15 below the plane of the bed 12, and in said hanger a vertical saw-shaft 38 is journaled, provided with a drive-pulley 39, and to the upper end of the said shaft a saw 40 is horizontally secured. The saw is located above the bed, and its position is such that its inner peripheral cutting-surface is practically in vertical alignment with the vertical saw 35 above it. A second hanger 41 is secured to the front face of the bed parallel with the hanger 37, the hanger 41 being located in front of the yoked extremities of the horizontal saw-shafts 29. In the hanger 41 a ver-

tical saw-shaft 42 is journaled, also fitted with a drive-pulley 43 and having a saw 44 horizontally attached to its upper end, which saw 70 is in horizontal alignment with the saw 40. The hanger 37 moves with the carrier to which it is secured, and the hanger 41 is capable of lateral movement upon the bed.

Between the opposed saw-carrying ends of 75 the horizontal shafts journaled in the intermediate and end carriers 14 and 16 two parallel tracks 45 are laid, which tracks are preferably angular or L-shaped in cross-section, the said tracks being located over the 80 lower saws 35 of the said carriers, and at the point where the tracks cross the said saws recesses 46 are created in the tracks, as is best shown in Fig. 2, in order that the lower saws 85 may engage with the edges of the boxes passed over the tracks. One of the tracks is rigidly attached to the bed and the other is laterally adjustable to and from the fixed track. The tracks 45 extend from the rear of the machine over the table 13. The adjustable track, however, is not attached to the table. Similar tracks 48 are laid between the horizontal saws 40 and 44, the inner face of the outer track being practically in vertical alignment with the outer face of the saw 95 35, connected with the carrier 15, as is best shown in Fig. 1. One of these tracks is also laterally adjustable, and each of the tracks is provided with a recess or slot in its vertical member to permit the horizontal saws 40 100 and 44 to engage with the box passed over the tracks.

The brackets held to slide upon the end carriers 15 and 16 have attached to their upper ends horizontal bars 49. The bars 49 are 105 laterally adjustable, and to the inner end of each bar a vertically-adjustable perpendicular arm 50 is secured, which arms are provided with shoes 51, integral with or attached to their lower ends. One of the arms 50 is located immediately over the space between the tracks upon which the boxes are to be slid in front of the vertical upper saws, the shoes 51 of the arm being adapted to bear against the upper surface of the box to be 115 trimmed and prevent the said box from vertical movement when the saws are acting thereon.

In the front of the machine, beneath the table, a drive-shaft 52 is journaled, being provided with a large pulley 53, connected by a belt 54 with the pulley of the vertical saw-shaft 38. A narrower pulley 55, also secured to the shaft 52, is connected by a belt 56 with the pulley of the vertical saw-shaft 42. A 125 third pulley 57, also attached to the shaft 52, is connected by a belt 58 with a pulley 59, attached, preferably, to the center of the lower horizontal saw-shaft connected with the intermediate carrier 14, each of the horizontal 130 saw-shafts being provided with a similar pulley. A wide pulley 60, secured to the drive-shaft 52, is connected by a belt 61 with the pulley of the lower saw-shaft upon the end

carrier 16. The drive-pulley 62 of the drive-shaft 52 may be connected therewith at any suitable point. The pulleys of the upper horizontal saw-shafts are driven in any suitable or approved manner from counter-shafts preferably located overhead.

The attachment of the pulleys 59 to the saw-shafts 29 is somewhat peculiar and is illustrated in Fig. 4. The bearing 28, in which the shaft is held to revolve at or near the center of the shaft, is provided with an annular channel 63, extending through the bearing, whereby the latter is practically divided into two sections, and at the channeled portion of the bearing the shaft 29 is provided with a longitudinal key-slot 64. The pulley 59 has inserted in its periphery, preferably at the center, a key 65, the lower end whereof passes down through the channel 63 and into the key-slot 64. It will thus be observed that the saw-shaft is capable of lateral movement and that while the shaft is being moved laterally it is kept revolving by the key connection with its pulley 59.

In operation the box, with its bottom nailed on flush with one end only, is placed lengthwise—that is, with the sides facing the front and rear of the machine—upon the front or forward end of the tracks 48, top down, as illustrated in dotted lines, Fig. 1. The box is then fed rearward in any approved manner until the horizontally-aligning saws are reached, whereupon the bottom of the box is engaged by the shoe 51 of the presser-arm 50, and in passing the saws the projecting cover edges and the unfinished bottom end of the box are neatly trimmed and rendered flush with the end boards. When the box reaches the rear of the tracks 48, it is moved by an attendant stationed at the rear of the machine, turned, and placed upon the rear ends of the tracks 45 crosswise, as is also shown in dotted lines, Fig. 1, and in this position the box is fed to the vertically-aligning perpendicular saws. The vertical saws as the box passes trim off any projection of the edges over the sides of the box at its top and bottom. Thus the box passes from the machine having all of its projecting edges made flush with its top, bottom, and sides.

In the event that a wide box is to be trimmed the sides or ends of the box, as the case may be, just before reaching the saws engage with the guide-arms 33, connecting the adjusting-bars 30, and force the said arms against the tension of the spring 34 to move a sufficient distance in the brackets to permit the passage of the box, and when the adjusting-rods are slid in their bearings by means of the yoke connection 32 of said arms with the saw-shafts the said shafts are carried with them, and the saws are thereby in every instance brought to the proper position to perform their work.

Having thus described my invention, I claim

as new and desire to secure by Letters Patent—

1. In a cigar-box-trimming machine, the combination, with a carrier, of brackets having their backs transversely beveled and secured to the carrier in an inclined position, a shaft mounted in the brackets, and a saw mounted on the shaft, substantially as described.

2. In a cigar-box-trimming machine, the combination, with a bracket and a saw-shaft mounted in the bracket and capable of a sliding movement therein, of sliding and spring-actuated adjusting-bars mounted in the said bracket and having their outer ends connected with the saw-shaft, and a gage-bar secured to the inner ends of the said bars, substantially as described.

3. In a cigar-box-trimming machine, the combination, with a bracket provided with parallel arms and a saw-shaft mounted in the arms and capable of a sliding movement therein, of sliding adjusting-bars mounted in the said arms, a yoke connecting the outer ends of the bars with the saw-shaft, a spring connected to the yoke and to one of the bracket-arms, and a gage-bar secured to the inner ends of the said bars, substantially as herein shown and described.

4. In a cigar-box-trimming machine, the combination, with a carrier, of an upper and a lower shaft mounted in bearings on the carrier, the inner end of the upper shaft being inclined downward and the inner end of the lower shaft being inclined upward, and saws on said shafts, substantially as herein shown and described.

5. In a cigar-box-trimming machine, the combination, with a stationary carrier and a movable carrier, of upper and lower shafts mounted in bearings carried by each of the carriers, and saws mounted on the shafts and having lateral and vertical inclinations, substantially as herein shown and described.

6. In a cigar-box-trimming machine, the combination, with a track and upper and lower brackets arranged at the sides of the rails thereof, of a saw-shaft journaled horizontally in each of the brackets, the upper shafts extending at one end above the rails, and adjusting-rods held to slide in each of the brackets, provided at one end with an attached gage-bar and connected at the opposite ends with the saw-shaft, as and for the purpose specified.

7. In a cigar-box-trimming machine, the combination, with upper and lower brackets, all the brackets being laterally adjustable and the upper brackets vertically adjustable, a track located between the opposed ends of the lower brackets, and sliding saw-shafts journaled in each bracket, the upper shafts extending at one end over the rails of the track and the lower shafts beneath the said rails, of spring-controlled adjusting-rods held

to slide in the brackets, gage-bars attached to one end of the adjusting-rods, and a connection, substantially as described, between the opposite ends of the adjusting-rods and the 5 saw-shafts, as and for the purpose set forth.

8. In a cigar-box-trimming machine, the combination, with upper and lower brackets, all the brackets being capable of lateral adjustment and the upper brackets of vertical 10 adjustment, a track located between the lower brackets, saw-shafts journaled in all of the brackets, the saw-carrying ends of the upper shafts extending over the rails of the track and the corresponding ends of the 15 lower shaft below said rails, the saw-carrying ends of the vertically-aligning shafts being made to approach each other closer than the opposite ends and the said saw-carrying ends being also laterally advanced, of adjusting-rods held to slide in the brackets, gage-bars secured to one end of the adjusting-rods, and a connection between the opposite ends 20 of the rods and the saw-shafts, as and for the purpose set forth.

25 9. In a cigar-box-trimming machine, the combination, with an adjustable bracket, a saw-shaft journaled in said bracket and capable of a sliding movement, and a track arranged beneath the saw-carrying end of the 30 shaft, of vertical saw-shafts, one located at each side of the rails of the track and provided at their upper ends with horizontally-located saws, substantially as shown and described.

35 10. In a cigar-box-trimming machine, the

combination, with an adjustable bracket, a saw-shaft journaled in said bracket capable of a sliding movement, and adjusting-rods held to slide in the bracket, provided with a gage-bar at one end and a connection with the saw-shaft at the opposite end, of a track located beneath the saw-carrying end of the saw-shaft, and a vertical saw-shaft arranged at the outer side of each rail of the track, the 40 saws being horizontally attached to the upper ends of the vertical shafts, as and for the purpose specified.

45 11. In a cigar-box-trimming machine, the combination, with a horizontal track and upper and lower saw-shafts, the saw-carrying 50 ends of the upper shaft extending over the rails of the track and the corresponding ends of the lower shafts extending beneath the rails of the track, the saw-carrying ends of each set of vertically-aligning shafts being made to 55 approach closer than their opposite ends, the said saw-carrying ends being also laterally advanced, of a second horizontal track, a horizontal saw-shaft, the saw-carrying end where- 60 of extends over one rail of the track and is laterally advanced and vertically depressed, and perpendicular saw-shafts arranged one at the outer side of each rail of the track and having attached horizontal saws extending through the rails of the track, substantially 65 as and for the purpose specified.
